UNITED STATES PATENT OFFICE

JACQUES MAISCH, OF NEW YORK, N. Y., ASSIGNOR TO H. R. MALLINSON & CO., INC., OF NEW YORK, N. Y., A CORPORATION OF DELAWARE

DESIGN FOR A SCARF OR SIMILAR ARTICLE

Application filed December 3, 1932. Serial No. 46,291. Term of patent 3½ years.

To all whom it may concern:

Be it known that I, JACQUES MAISCH, a citizen of France, residing at No. 1 West 67th Street, in the borough of Manhattan, city of New York, county of New York, and State of New York, have invented a new, original, and ornamental Design for a Scarf or Similar Article, of which the following is a specification, reference being had to the accompanying drawing, forming part thereof.

The figure is a plan view of a scarf showing my new design.

I claim:

The ornamental design for a scarf or similar article, as shown.

JACQUES MAISCH.
